UNITED STATES PATENT OFFICE.

WILLIAM VOGEL, OF NEW YORK, N. Y.

SHOE-BUTTONER.

1,306,790.

Specification of Letters Patent. Patented June 17, 1919.

Application filed September 27, 1913. Serial No. 792,083.

To all whom it may concern:

Be it known that I, WILLIAM VOGEL, a citizen of the United States, and a resident of No. 558 West 151st street, in the borough 5 of Manhattan, county, city, and State of New York, and whose post-office address is No. 82 Nassau street, in the said borough of Manhattan, county, city, and State of New York, have invented certain new and useful 10 Improvements for Shoe-Buttoners, set forth in the following specification.

This invention relates to means for buttoning shoes. An object of the invention is to provide for the manipulation of a shoe 15 buttoner in a manner so as to preserve the button-hole; to cause the button to be entered into the button-hole with convenience and despatch; and to make possible a quick buttoning action without a tendency to twist 20 off the buttons or discommode the wearer. To the above ends there is contemplated within the invention the employment of a button-claw formed on a specially shaped lever, a portion of which operates as a cam 25 with the button-hole as a cam follower and with an entire elimination of the usual rotary motion in shoe buttoning associated with the use of a button-hook. Further objects of the invention include novel structural 30 embodiments and combination of various elements through the medium of the structural form.

The above will be pointed out more in detail in the following claim which should be 35 read in connection with the illustrative embodiment of the invention described in the following specification and shown in the accompanying drawings which form a part of this application, in which like characters 40 designate corresponding parts, and in which Figure 1 is a front elevation of the device; Fig. 2 is a section through line II—II of Fig. 1; Fig. 3 is a section corresponding to Fig. 2 and also including a section through 45 a shoe-upper and showing a method of employing the shoe-buttoner; and Fig. 4 is a sectional view through line IV—IV of Fig. 3.

The body portion 1 of the shoe-buttoner 50 is formed spoon-shaped into the proper formation to serve the function of a shoe-horn and advantage is taken of the well known concavo-convex formation of a shoe-horn to provide a stiff unyielding shank 2 by stamping a continuation of the metal of the body 55

portion 1 into the formation of a channel-iron so that extreme stiffness with a minimum amount of metal is provided. This shank 2 toward its lower portion is bent longitudinally into a curved formation forming the cam portion 3. Below the cam portion 3 the sheet metal is stamped outwardly to form the heel 6, from which the metal continues to extend outwardly in two lips 4 and 5 each of a concavo-convex cross-section 60 to form a powerful unyielding claw C.

It is preferable that the size of the claw C be in width as well as in length approximately the size of the underside of an average shoe-button 8 such as that shown at 70 attached to the shoe-upper 7.

Fig. 3 shows the method of employing the shoe-buttoner. The claw C is thrust through the button-hole 9 and the claw C is gripped under the button 8. A downward pressure 75 on the body portion 1 causes the shank 2 to act as a lever and the cam portion 3 coöperating with the outer edge of the button-hole 9 multiplies the power of the operator's hands and conveniently draws the two margins 10 and 11 of the shoe-upper together a sufficient amount to make the button 8 aline with the button-hole 9. At the same time the cross sectional formation of the cam 3 holds the button-hole open the proper 80 amount to facilitate the entrance of the button 8 and by presenting a comparatively broad curved surface to the outer edge of the button-hole prevents injury to the same. With the parts in the position shown in Fig. 90 3 a slight jerk on the shoe-button causes the button 8 to jump into the button-hole 9 and at the same time causes the claw C to disengage the button.

What is claimed and what is desired to 95 be secured by the United States Letters Patent is:

As an article of manufacture, a combined shoe-buttoner and shoe-horn consisting of a single sheet metal stamping and comprising 100 a wide body portion of curved cross section; an elongated shank of channel-iron cross section with its concavity on the same side of but of shorter radius of curvature than the concavity of said body portion, said 105 shank being so curved, in the direction of its length, as to provide a cam portion extending in a direction approaching 90° from the initial direction of said shank, both the cross-sectional curvatures and the longitudi- 110

nal curvatures of the body portion and the shank being such that the body portion blends gradually into the shank portion and the structure is free from abrupt angles in 5 the body portion and the shank; said shank being provided with a claw extending outwardly from the end of said shank for gripping the under face of a shoe button, whereby a downward movement of the free end 10 of said shank causes it to act as a lever, to

cam the shoe margins together and snap the shoe button through the button hole.

In witness whereof, I have signed my name to this specification, in the presence of two subscribing witnesses.

WILLIAM VOGEL.
